UNITED STATES PATENT OFFICE.

WILLIAM L. BEAN, OF WEST HAVEN, CONNECTICUT, ASSIGNOR TO McCLELLON LOCOMOTIVE BOILER COMPANY, OF BOSTON, MASSACHUSETTS, A CORPORATION OF MASSACHUSETTS.

LOCOMOTIVE BOILER.

Application filed April 21, 1923. Serial No. 633,632.

This invention relates to locomotive boilers and more particularly to boilers of that type wherein the firebox embodies walls of water-containing tubes and the object is to provide certain improvements in a firebox of this type to make it more durable and effective in service.

My invention will best be understood by reference to the following description of an illustrative embodiment thereof shown by way of example in the accompanying drawings, wherein:

Fig. 1 is a rear end elevation of the boiler;

Fig. 2 is a section on the line 2—2 of

Fig. 1;

Fig. 3 is a central longitudinal section through the firebox and the rear portion of the barrel of the boiler; and

Fig. 4 is a side elevation of one of the rear wall tubes.

Referring to Fig. 3, the boiler there shown comprises the usual barrel 5 through which extends the flues or fire tubes 7 and a firebox made up principally of small sections, preferably thin walled cylindrical tubes, which as contrasted with a standard firebox consisting of spaced sheets provides for the elimination of stay bolts, an enlarged heating surface and greater strength to resist pressure.

The firebox comprises a crown chamber which preferably consists (see Fig. 1) of a central drum 9 and two lateral drums 11 which have their adjacent sides flattened and fitting together with the central drum 9 fitting between the lateral drums 11 in the manner of a keystone to form a crown chamber of a general sector shape having a bottom which will remain well covered with water and preserving cylindrical exterior walls adapted to resist the pressure of steam within the same. The ends of these drums may be somewhat distorted at their front and rear ends, as more fully described in the patent to J. M. McClellon, No. 1,248,356, dated Nov. 27, 1917, fitting together block-like at each end. The rear ends, as shown in Fig. 1, are closed by dished heads 13 and 15 while the front ends are open and are received in the open end of the barrel 5 and collectively close an upper segmental portion thereof, the portion of the barrel beneath the

drum being closed by the flue sheet 17 fitting in the barrel and under the end of the crown chamber formed by the three drums.

Preferably, as best shown in Fig. 3, the upper portion of the barrel is cut away where it joins the crown chamber and the lower portion extends rearwardly as a segmental extension and is riveted to the sides of the crown chamber which is thus joined to the barrel by a sort of splice or scarf joint and is supported along a considerable lengthwise zone by the heavy barrel shell. The space defined by the rearward extension of the barrel shell beyond the flue sheet 17 and by the crown chamber serves as a combustion chamber and may be lined with water tubes 21 opening at their upper ends to the crown and having blind lower ends overlying the barrel shell and connected therethrough to a water chamber 23 which may consist of a sheet secured to the lower portion of the barrel shell and having communication with the portion of the barrel forward of the flue sheet at one end as indicated at 25 and at its rear end opening into a throat chamber defined by a forward sheet 27 and a rear throat sheet 29 connected to the barrel shell.

The throat chamber is in communication with a foundation chamber or mud ring 31 running along the two sides and the rear of the firebox and which may consist, as best shown in Fig. 1, of a channel-shaped section closed on the outer side by a plate 33. The side walls of the firebox extend between the foundation chamber and crown chamber and preferably consist of thin walled cylindrical tubes 35 set side by side substantially in contact and communicating at their lower and upper ends respectively with the interior of the foundation chamber and of the crown. In the embodiment of the invention here illustrated this connection is made by providing the tubes with reduced ends which enter suitable openings in the top of the crown chamber and in the sides of the lateral drums 11 and which are expanded or otherwise suitably secured in these openings. As it is desirable to have the rear wall of the firebox slope rearwardly from top to bottom, as indicated in Fig. 3, short sections 37 may be provided rising from the foundation chamber 31 adjacent the rear end of the fire-

box and serving to complete the side walls there and these tubes may be provided with nipple connections 39 as shown in Fig. 1 to the adjacent tubes 35 which extend to the crown chamber. Arch tubes 41 may also be provided extending diagonally downward through the firebox from the crown to the throat chamber and may support the usual fire brick arch for baffling the flame.

10 An important feature of my invention relates to the construction whereby the parts of the firebox are secured in position in such manner as to withstand without deterioration the racking shocks and poundings to 15 which a locomotive boiler is subjected in its travel over the road. As already stated, I prefer to connect the crown chamber to the barrel in the manner set forth in order to provide a long joint or connection between 20 the crown and the barrel tending to hold the former rigidly aligned with the heavy and well supported barrel. Further to support the crown and to eliminate a strain upon the water tubes and their connections to the 25 crown I provide, as best shown in Fig. 1, pillars supporting the crown independently of these water tubes and conveniently such pillars may consist of two T sections 43 extending from the foundation chamber 31 and sloping somewhat inwardly to conform 30 to the inclination of the rear wall of the firebox and secured at their upper ends in underriding relation to the two lateral crown drums 11. By this arrangement space is 35 provided between the two pillars to give access to the fire door of the locomotive and to further increase the rigidity of the structure and to provide a support for the central crown drum 9 I provide a girder 45 40 extending beneath the pillars and on which the rear end of the central drum 9 is seated. The flanges of the T sections 43 contribute to the rigidity of the pillars and as best shown in Fig. 2 they may extend inwardly 45 and be housed between the tubes which are utilized in the rear wall of the boiler.

The firebox door may be suitably framed as by a lower chamber 47, having an open bottom received in a suitable opening in the 50 top of the foundation chamber 31 as seen in Fig. 3, a pair of side columns 49 opening from this chamber and a transverse header 51 between them.

55 The rear wall of the firebox may embody in its construction suitable water connecting tubes extending between the foundation chamber and the crown. On account of the inward slope of the rear wall from bottom to top and the inward inclination of the side walls, as best shown in Fig. 1, the construction of such a rear wall presents many problems. To provide for a most effective connection of water connecting tubes between the foundation chamber or the firebox door

frame and the crown I prefer to utilize relatively small tubes of uniform diameter which will be relatively widely spaced as compared with the side wall tubes 35, the space between these tubes being closed at the rear of the firebox by suitable nonconducting material such as fire brick (not shown). This construction is practicable particularly since the rear wall of the firebox is not subjected to such high heats as the side walls and since the walls of large tubes 35 at the side of the firebox provide for the circulation of an effective volume of water and for a large heating surface. The reduction in area of the heating surface which might be expected from the smaller size of the rear wall tubes may be somewhat compensated for by so applying the refractory material as to leave a relatively large portion of the circumferences of the tubes exposed.

65 By the use of tubes of uniform diameter in the rear wall as described the longer tubes 53 (see Fig. 4) extending between the foundation chamber and the crown and the shorter tubes 55 extending between the framing of the firebox and the crown may be so bent as to present their ends substantially normally or perpendicularly to these elements and in particular the tubes may be given a double curvature as illustrated in 70 Figs. 3 and 4 of the drawings to enter the upper portion of the foundation chamber and the lower wall of the firebox perpendicularly thereto. These tubes may then be 75 expanded in suitable openings and upset or rolled over on the interior thereof. It 80 will be clear by reference to Fig. 3 that the crown adjacent the rear end is definitely spaced from the foundation chamber by the supporting frame comprising the pillars 43 and girder 45 and the upset ends of the tubes 85 act in opposition to this support so that an 90 effectual tight connection is assured while the double curvature of the tubes provides a certain springiness therein facilitating 95 their incorporation in the assembly and contributing to the wearing qualities of the 100 boiler and its frame.

105 From the preceding description it will be seen that in the embodiment of the invention described the main portions of the firebox are held in position and definitely related to the heavy barrel 5 supported on the framing of the locomotive and to the foundation chamber 31 and that this is done independently of the relatively light tubes 110 which go to form the walls of the firebox so that all the parts of the firebox are adapted 115 to resist the severe racking and pounding strains to which they are subjected in the 120 passage of the locomotive over the road.

125 Having described in detail a particular embodiment of my invention as herein illustrated in order that the principles might be

clearly understood, what I claim as new and desire to secure by Letters Patent I shall express in the following claims.

Claims:

- 5 1. A locomotive boiler comprising a barrel and a firebox comprising a crown chamber communicating at its forward end with said barrel and supported in part thereby, a foundation chamber also communicating at its forward end with said barrel, water tubes extending between foundation and crown and providing the walls of the firebox and pillars exterior of the walls extending between foundation and crown at the rear 10 of the latter and supporting the rear portion of the crown independently of said tubes.
2. A locomotive boiler comprising a barrel and a firebox comprising a crown chamber embodying a central and lateral longitudinally extending drums communicating at their forward ends with said barrel, a foundation chamber also communicating at its forward end with the barrel, water tubes 15 extending between the crown and the foundation and providing walls for the firebox, pillars extending between the rear heads of the lateral drums and the foundation to support the crown independently of said tubes and a cross connection extending between said pillars and supporting the central drum and also serving as a tie between the pillars, the space beneath said connection and between the pillars providing for the fire door.
3. A locomotive boiler comprising a barrel and a firebox comprising a crown chamber communicating at its forward end with said barrel and supported in part thereby, a foundation chamber also communicating at 20 its forward end with said barrel, water tubes 25 extending between foundation and crown and providing the walls of the firebox, pillars exterior of the walls extending between foundation and crown at the rear of the latter and supporting the rear portion of the crown independently of said tubes.
4. A locomotive boiler comprising a barrel and a firebox comprising a crown chamber communicating at its forward end with said barrel and supported in part thereby, a foundation chamber also communicating at its forward end with said barrel and extending rearwardly beyond the rear end of the crown, water-containing walls for the 30 firebox comprising tubes extending between crown and foundation and pillars located outward of the rear wall of the firebox extending between foundation and crown to support the latter independently of the tubes 35 and relieve the same of column loads and of the strains longitudinal of the boiler incident to its use.
5. A locomotive boiler comprising a barrel and a firebox comprising a crown chamber communicating at its forward end with said barrel and supported in part thereby, a foundation chamber also communicating at its forward end with said barrel, water tubes 40 disposed substantially upright but not vertical between said crown and foundation and providing side and rear water walls for the firebox and pillars exterior of the walls extending between foundation and crown at the rear of the latter and supporting the 45 rear portion of the crown independently of said tubes.

In testimony whereof, I have signed my name to this specification.

WILLIAM L. BEAN.
